(57) **CLAIM**

The ornamental design for the armband carrier with window, as shown and described.

DESCRIPTION

FIG. 1 is a front elevational view of the armband carrier with window showing my new design;

FIG. 2 is a top plan view thereof;

FIG. 3 is a bottom plan view thereof;

FIG. 4 is a rear elevational view thereof;

FIG. 5 is a left end view of FIG. 1;

FIG. 6 is a right end view of FIG. 1;

FIG. 7 is a front elevational view of a modified embodiment of the armband carrier with window;

FIG. 8 is a top plan view of the modified armband carrier with window of FIG. 7;

FIG. 9 is a bottom plan view of FIG. 7;

FIG. 10 is a rear elevational view of FIG. 7;

FIG. 11 is a left end view of FIG. 7;

FIG. 12 is a right end view of FIG. 7;

FIG. 13 is a front elevational view of a further modified embodiment of the armband carrier with window;

FIG. 14 is a top plan view of the further modified armband carrier with window of FIG. 13;

FIG. 15 is a bottom plan view of FIG. 13;

FIG. 16 is a rear elevational view of FIG. 13;

FIG. 17 is a left end view of FIG. 13; and,

FIG. 18 is a right end view of FIG. 13.
